UNITED STATES PATENT OFFICE

EMILE PIQUEREZ, OF PARIS, FRANCE, ASSIGNOR TO ALEMITE CORPORATION, OF CHICAGO, ILLINOIS, A CORPORATION OF DELAWARE

LUBRICANT COMPRESSOR

Application filed April 15, 1925, Serial No. 23,284, and in France June 6, 1924.

This invention relates to lubricant compressors, and more specifically to a triple action compressor for delivery of lubricant under very high pressure, thus making possible certain and complete lubrication of mechanical elements regardless of the resistance offered to the flow of lubricant.

According to the invention, the lubricant is first drawn in by suction, and then forced on in successive steps so as to obtain a very high final pressure all requiring the exertion of only small force to facilitate direct and rapid operation of the devices manually without the intermediary of a lever or screw.

The intake of lubricant and its double compression is produced in the embodiment disclosed, by a single piston having reciprocating rectilinear movement working with two faces in opposite directions, and the spaces into which the lubricant passes, decrease gradually by successive stages, to obtain the above mentioned stages of pressure increase.

In the accompanying drawings:

Figs. 1, 2 and 2^a show one embodiment of the invention, Fig. 1 being a central longitudinal section, Figure 2 a section on the line 2—2 of Figure 1, and Fig. 2^a a horizontal section of the piston only.

Fig. 3 is a longitudinal section of a second embodiment.

The embodiment of the invention illustrated in Fig. 1 comprises a cylindrical lubricant reservoir 1, provided with a threaded cover 2 and containing a follower 3 provided with a seal 4. An axial rod 5 passes through cover 2 and piston 3 and carries an external handle. The rod extends into the body 6, threaded into the reservoir 1 to form the bottom thereof. A bore 7 is formed in body 6, closed at its upper end by a threaded plug 8 provided with a packing 9. A piston 10 reciprocates in the cylinder bore 7, the said piston being formed by an enlargement of the rod 5, which rod extends beyond piston 10 as a piston 11, eccentric with respect to piston 10 within the periphery of which it is tangentially inscribed. (See Fig. 2^a.)

A transverse inlet 12 formed in body 6 level with the bottom of the reservoir, con-

nected compression cylinder 7 with the reservoir 1. A small passage 13 formed in body 6 parallel to the central bore 7, communicates therewith at its upper end through port 14, and at its lower end through port 15, opening into an annular groove 15^a positioned below opening 12 at such a distance that it will be covered by piston 10 when said opening is uncovered. The rod 11 at its lower end passes through an annular valve 16 housed in a cylindrical chamber 17, in the body 6, closed by threaded cap 18, provided with a packing 19 around the rod 11.

Valve 16 is provided with a resilient set-in seat 20, which is firmly pressed against collar 21 formed in the upper face of the chamber 17 by the action of a spring 22 resting on cap 18. A lateral outlet 23 at the bottom of body 6 delivers the lubricant.

There is preferably also provided a safety means which comprises a ball 24 set in a socket 25 in the body 6 below the cap 8 and communicating with cylinder 7 and reservoir 1. The ball is normally held in its closed position by a short spring 26, to relieve the pressure in the upper end of the compression cylinder.

The operation is as follows:

With the piston at the top, passage 13 is full of lubricant, as well as the part of the cylinder between bore 7 and the eccentric rod 11, down to valve 16. Pushing the handle of rod 5 to force the piston down, develops suction over the same, and port 12 is uncovered so that lubricant flows into cylinder 7. Simultaneously the descent of the piston compresses the lubricant below the same and opens valve 16 so that the lubricant is discharged under high pressure through chamber 17 and outlet 23. The advance stroke of piston, therefore, produces simultaneously, the double action of suction intake and high pressure discharge.

Now, when rod 5 is pulled back, the piston rises, compressing the lubricant in the cylinder into passage 13 and its communicating ports. At the end of this upward movement there is thus below the piston, lubricant already compressed, which upon the next advance stroke will be further compressed as 100

above pointed out, so as to discharge lubricant under very high pressure.

There is thus obtained a three stage successive action on the lubricant, comprising, first, suction intake and the two stages of compression between opposite ends of the piston with areas and capacity decreasing successively. It will be observed that the final pressure thus obtained can be very high.

10 The safety means 24 only operates when by reason of some obstruction, the pressure in the upper end of the cylinder exceeds the maximum safe limit. At such times the pressure forces the ball valve open and partial return of lubricant to reservoir 1 results.

15 The modifications of Fig. 3 involves the use of a compression means independent of the cylindrical reservoir. In this embodiment reservoir 1, provided with a cover 2 and the follower 3, is threaded into a base 27, having a flat side wall 27^a pierced by a tubular spur 28 on body 6, for which it forms a pintle permitting body 6 to the swung up beside reservoir 1. A packing 29 pressed against wall 27^a by a spring 30 held by a nut 31, assures a tight joint.

20 The port 12 in stud 28 connects reservoir 1 with cylinder 7, in which is piston 10, having the eccentric lower portion having a threaded end receiving a stop nut 32, and a rigid tube 33 provided with a lateral aperture 33^a and carrying at its outer end a standard coupling 34.

25 Cylinder 7 is closed by a plug 8 threaded into its upper end. As in the first described modification, body 6 has the by-pass 13 parallel to cylinder 7, communicating therewith through ports 14 and 15. At its lower end the body 6 provides a housing closed by a threaded cap 18, pierced by tube 33 and provided with packing 19, held by a spring 35 abutting at its upper end against nut 32.

30 The eccentric portion 11 of the piston passes through valve 16 provided with its in-set resilient seat 20, bearing on the seat 21 under the action of spring 22, resting at its bottom in an annular groove 17^a in the body 6.

35 In this embodiment the pressure relief ball 24 is housed in a socket 25, and held in place by spring 26, socket 25 communicating with reservoir 1 through passage 36, opening into port 12.

The operation is as follows:

With the device filled with lubricant, as one 40 pulls on cylinder 1, spring 35 will be compressed and suction will develop above the piston. Port 12 is then uncovered and the lubricant enters cylinder 7. At the same time the piston compresses lubricant between its self and valve 16 and when this pressure is high enough the lubricant is discharged into chamber 17 from which it passes into tube 33 through opening 33^a.

45 The return stroke is produced by spring 35 pressing on nut 32 to raise piston 10 and

bypass the lubricant above the same through passage 13. As in the preceding modification, the two strokes of the piston produces the triple action of suction intake, low compression and high compression. The pressure relief means 24 will operate precisely as in the first embodiment. In both embodiments the cover 2 should have an air vent 2^a.

50 Without further elaboration, the foregoing will so fully explain the gist of my invention, 75 that others may, by applying current knowledge, readily adapt the same for use under various conditions of service without eliminating certain features which may properly be said to constitute the essential items of 80 novelty involved, which items are intended to be defined and secured by the following claims.

I claim:—

1. A lubricant compressor comprising a 85 differential area piston having a large end and a small end, a cylinder therefor, a lateral port uncovered at the end of the out stroke to fill the large end, by-pass for carrying lubricant from the large to the small end 90 during the return stroke, the discharge end of said by-pass being covered by the piston during most of the out stroke, an annular spring-held check valve controlling the discharge from the small end, a pressure relief 95 valve at the large end, and a reservoir supporting said cylinder and surrounding said intake port.

2. A lubricant compressor comprising a 100 differential area piston having a large end and a small end, a cylinder therefor, a lateral port uncovered at the end of the out stroke to fill the large end, a by-pass for carrying lubricant from the large to the small end during the return stroke, the discharge end of said by-pass being covered by the piston during the out stroke and an annular spring-held check valve controlling the discharge from the small end.

3. A lubricant compressor comprising a 110 differential area piston having a large end and a small end, a cylinder therefor, a lateral port uncovered at the end of the out stroke to fill the large end, a by-pass for carrying lubricant from the large to the small end during the return stroke, the discharge end of said by-pass being covered by the piston during the out stroke, an annular spring-held check valve controlling the discharge from the small end, and a pressure relief valve at the large end.

4. A lubricant compressor comprising a 120 differential area piston, having a large end and a small end, a cylinder therefor, a lateral port uncovered at the end of the out stroke to fill the large end, a by-pass for carrying lubricant from the large to the small end during the return stroke, the discharge end of said by-pass being covered by the piston during the out-stroke, an annular spring-held 125

check valve controlling the discharge from the small end, a pressure relief valve at the large end, and a reservoir surrounding said intake port and relief valve.

5. A lubricant compressor comprising a differential area piston, a cylinder therefor, a lateral port uncovered at the end of the out stroke to fill the large end, a by-pass for carrying lubricant from the large to the small end during the return stroke, the discharge end of said by-pass being covered by the piston during the out stroke, and a check valve controlling the discharge from the small end.

10 6. A lubricant compressor comprising a differential area piston having a large end and a small end, a cylinder therefor, a lateral port uncovered at the end of the out stroke to fill the large end, and a by-pass for carrying lubricant from the large to the small end during the return stroke, the discharge end of said by-pass being covered by the piston during the out stroke.

15 7. A lubricant compressor comprising a low pressure cylinder for lubricant, a high pressure cylinder for lubricant, a single plunger reciprocating in both cylinders to discharge lubricant therefrom, said low pressure cylinder discharging into said high pressure cylinder, and pressure relief means intermediate said high and low pressure cylinders.

20 8. In a device of the character described, in combination, a chamber having an outlet passageway, an auxiliary compartment between said chamber and said outlet passageway and in communication with both, a check valve between said compartment and said chamber, and a pair of pistons operating in and complementary each to said passageway and auxiliary compartment, respectively.

25 9. A lubricant compressor provided with axially aligned normally intercommunicating high and low pressure cylinders, a container for supplying lubricant to the low pressure cylinder, a plunger reciprocable in said high and low pressure cylinders and adapted to cut off communication between said cylinders, the effective area of said plunger in said low pressure cylinder being greater than its effective area in said high pressure cylinder, means for reciprocating said plunger, and check valve means permitting flow of lubricant from said low pressure cylinder to said container upon a predetermined difference in pressure on the opposite sides thereof.

30 10. In a lubricant compressor, the combination of a chamber containing lubricant, a cylinder having two axially connected portions and communicating with said chamber, a check valve at the outlet of said cylinder, a plunger having two piston parts of different effective area, one of said parts being operable in each of said portions of said cylinder, one of said piston parts cutting off communication between said cylinder portions

and the other piston part cutting off communication between said cylinder and said chamber when said plunger is reciprocated, and a valve controlled bleed in one of said portions for permitting escape of lubricant therefrom to said chamber.

35 11. In a lubricating device, in combination, a chamber for containing a lubricant, a cylinder having two axially connected portions and communicating with said chamber, pistons operable in said cylinder portions, an outlet from one of said cylinder portions and a valve controlled bleed from one of said cylinder portions into said chamber.

40 12. In a lubricating device, in combination, a chamber for containing a lubricant, a cylinder having two axially connected portions and communicating with said chamber, pistons operable in said cylinder portions, a bleed from one of said cylinder portions into said chamber, and a discharge nozzle connected with said cylinder.

45 13. A lubricating device including a chamber for containing a lubricant, a cylinder having an outlet, a plunger operable in said cylinder, means for connecting the latter to a member to receive the lubricant, an auxiliary compartment in open communication with said cylinder, and means for introducing lubricant into said compartment in increments for maintaining a constant supply for said cylinder.

50 14. A lubricating device including a chamber for containing a lubricant, a high pressure cylinder communicating with said chamber and having a piston, an auxiliary cylinder communicating with said chamber and said high pressure cylinder, simultaneously operating pistons operable in both of said cylinders, and a discharge conduit leading from said high pressure cylinder.

55 15. A lubricating device including a chamber for containing a lubricant, a high pressure cylinder communicating with said chamber and having a piston, an auxiliary cylinder communicating and in axial alignment with said chamber and said high pressure cylinder, pistons operable in both of said cylinders, and a discharge conduit leading from said high pressure cylinder.

60 16. In a device of the character described, in combination, a chamber having a high pressure cylinder, an auxiliary cylinder between said chamber and said high pressure cylinder, and in communication with both, a check valve between said auxiliary cylinder and said chamber, a pair of pistons complementary each to said cylinders, respectively, a plunger rod for jointly operating said pistons, and a follower in said chamber and carried by said plunger rod.

In witness whereof, I hereunto subscribe my name, this 23d day of March, 1925.

EMILE PIQUEREZ.
